UNITED STATES PATENT OFFICE

GEORGE W. HUHNERKOCH, OF REDWOOD FALLS, MINNESOTA

SUSPENSORIAL DEVICE FOR ARTIFICIAL LEGS

Application filed May 9, 1929. Serial No. 361,729.

My invention relates to suspensorial devices for artificial legs. It relates more particularly to such devices for use in cases of amputation of the leg above the knee. A common manner of suspending or attaching artificial legs is by means of a harness, a portion of which is often passed over both shoulders with the result of producing transverse strains across the shoulder which is opposite 5 the one above the amputated leg. An object 10 of this invention is to substitute for the customary harness, a rigid belt made of metal or other material capable of retaining its shape, with straps depending from the belt 15 for attachment of the artificial leg and with a suspender extending up from the belt over the shoulder which is above the artificial leg.

The full objects and advantages of my invention will appear in connection with the 20 detailed description thereof, and the novel features of my inventive idea will be particularly pointed out in the claims.

In the accompanying drawings which illustrate a practical embodiment of my invention, —

Fig. 1 is a view showing the device in position upon the body of the wearer. Fig. 2 is a perspective view of the device on an enlarged scale. Fig. 3 is a fragmentary elevational view showing a rigid belt and securing strap therefor. Fig. 4 is a view in horizontal section on the line 4—4 of Fig. 3. Fig. 5 is a view in vertical section on the line 5—5 of Fig. 3.

As shown in the drawings and as will be evident particularly from Figs. 4 and 5, the device includes a rigid unyielding belt 10 of metal or other suitable material which is capable of retaining its shape. This belt is covered 35 with a protective casing 12 which can be removed from time to time and replaced with a new casing. As shown, this protective casing consists of cloth which is held in place on the belt by stitching 14 placed on the outer side. The two ends of the belt 10 overlap and are provided respectively with straps 16 and 40 18, one of which carries a buckle 20 and the other of which is provided with a series of holes 22 so that the belt may be properly adjusted around the waist of the wearer. These

two straps are located at one side of the belt and at the opposite side thereof a depending strap 24 is secured. A strap 26 provided with a buckle 27 for adjustment has its ends secured respectively to the front and back of the belt 10 so as to pass between the crotch of the wearer when the device is in place. The upper end of a depending strap 28 is looped around the central portion of the strap 26 which portion is rounded so that the strap 28 may have some sliding movement. The lower end of the strap 28 is provided with holes 30 for attachment to the inside of an artificial limb 32 while the lower end of the strap 24 is provided with holes 34 for attachment to the outside of the artificial limb. The ends of an upwardly extending suspender 36 are attached to the belt 10, one of these ends being attached between the place of attachment of the strap 24 and the front end 70 of the strap 26 while the other end of the suspender is attached between the place of attachment of the strap 24 and the back end of the strap 26. The suspender 36 is provided with a buckle 38 for adjustment. It 75 will be noted that the suspender passes directly over the shoulder which is above the amputated leg, thereby avoiding transverse strains which are apt to result when suspender 80 are passed over the opposite shoulder.

I claim:

1. A suspensorial device for artificial legs comprising a rigid belt for encircling the waist of the wearer, a flexible strap having one of its ends secured to the front of said belt and its other end secured to the back of said belt, said strap being adapted to pass between the crotch of the wearer, a flexible strap depending from the central portion of said crotch strap for attachment to the inside of the artificial leg and a flexible strap depending from the side of said belt for attachment to the outside of the artificial leg.

2. A suspensorial device for artificial legs comprising a rigid belt for encircling the waist of the wearer, a strap having one of its ends secured to the front of said belt and its other end secured to the back of said belt, said strap being adapted to pass between the crotch of the wearer, a strap depending from 100

the central portion of said crotch strap for attachment to the inside of the artificial leg, a strap depending from the side of said belt for attachment to the outside of the artificial leg, and a suspender extending up from said belt for passing over the shoulder which is above the artificial leg, one end of said suspender being attached between the place of attachment of said side strap and the front end of said crotch strap while the other end of said suspender is attached between the place of attachment of said side strap and the back end of said crotch strap.

In testimony whereof I hereunto affix my signature.
